CHANGEOVER MECHANISM FOR MOTION
PICTURE MACHINESIvory H. Crabtree, Toppenish, Wash., assignor
of three-fourths to Lottie P. Crabtree, Toppen-
ish, Wash.

Application October 16, 1929, Serial No. 399,949

8 Claims. (Cl. 88—17)

This invention relates to automatic control mechanism for motion picture projecting machines where such machines are used in duplicate and operate alternately, and it refers particularly to mechanism for changing over from the operating machine to the idle machine at the end of a reel of film so as to provide continuous and uninterrupted projection.

The principal object of the present invention is to provide a mechanism that is automatic in its changeover; which operates to start the idle machine when the film in the operating machine is nearly run out, and then, after the started machine has attained proper speed, simultaneously to open its dowser and to close that of the other machine.

It is also an object in one arrangement of the invention, to provide means operating automatically to energize a signal device to give the operator warning of the approach of the end of a film and to give ample time for manually closing the arc of the idle machine. In another embodiment, I provide for automatically closing the arc.

A further object of the invention is to provide novel switch mechanisms in connection with the unwinding of the film from the supply reel for controlling the buzzer or arc switch closing circuits and also the change over circuits from one machine to another.

Other objects of the invention reside in the provision of manual or push button switches for use when desired in lieu of the automatic means for controlling the change over devices.

Other objects of the invention reside in the details of construction and combination of parts, as will hereinafter be described.

In accomplishing these objects, I have provided the improved details of construction, the preferred forms of which are illustrated in the accompanying drawings, wherein—

Figure 1 is a diagrammatic illustration of the entire change-over system, showing the various circuit connections between the reel switches, motors, solenoids and manual control apparatus.

Figure 2 is a diagram of what is termed the buzzer circuit.

Figure 3 is a diagram of the motor control circuits.

Figure 4 is a diagram of the dowser reversing and control circuits.

Figure 5 is a diagram of a circuit for automatically striking the arc of the idle machine to be used in lieu of the manual control.

Figure 6 is a sectional view through a reel and

magazine therefor, particularly illustrating the automatic switch mechanisms contained within the reel.

Figure 7 is a horizontal section taken on the line 7—7 in Figure 6.

Figure 8 is a side view of the trigger frame on the reel.

Figure 9 is a cross section on the line 9—9 in Figure 6.

Figure 10 is a front view of the signal switch.

65

Figure 11 is a front view of the dowser, partly broken away for better illustration.

Figure 11a is a section on line 11a—11a of Figure 11.

Figure 12 is a back view of the dowser.

70

Referring more in detail to the drawings—

P¹ and P², as shown in Figure 1, respectively, designate the picture projecting machines which, in use, would be arranged side by side within a projection room. These machines are operated by separate electric motors M¹ and M² and light for the projectors is provided by passing an electric circuit through the arc electrodes E—E' of the machine P¹, and E^a—E^b of the machine P². A direct current circuit for the arcs flows through the wires 1 and 2 which have connection, by means of wires 3 and 4, with the arc electrodes E—E' and, by means of wires 5 and 6, with electrodes E^a and E^b. The arc circuit for projector P¹ is under control of a manually movable switch lever 7 interposed on wire 4 and adapted to be thrown into and from closed relation with contacts 8. Likewise, the arc circuit of the projector P² is under control of a similarly operated switch lever 9 interposed in wire 5 and movable from and against contacts 10 to break or close the circuit.

Each projecting machine in this instance embodies the usual projector magazine 11, an upper reel 12 on which the film strip is carried and a lower reel 13 onto which it is wound; it being understood that this winding of the film from one reel to the other is done by means of the usual driving connection with the machine motor.

Also, in accordance with the present invention, there is associated with each machine, a dowser mechanism, later to be described in detail, including a shutter that is movable from and across the line of light projection for cutting off the beam of light to the projection screen; these shutters of the two associated machines being so actuated that, unless otherwise manipulated, opening of either one is simultaneous with closing of the other. The present invention also

contemplates use of the governor mechanism with 110

which each projection machine is already equipped, for controlling certain switches which close and open the dowser circuits; the particular governor mechanisms used are not described or 5 illustrated in detail in the present invention, but are diagrammatically designated at 18g in Figures 1 and 4, and are connected to their switches by linkage as at 19. Without going into a detailed description, it is thought sufficient to say that, 10 when a machine attains its proper operating speed, its governor will have spread sufficiently to actuate the switch associated therewith to close a circuit through the dowser actuating mechanisms. Mercury switches suitable for this purpose have been diagrammatically illustrated in 15 Figures 1 and 4 wherein 20^a and 20^b designate the pivotally mounted mercury tubes each having operative connection through a suitable linkage 19 with its governor and adapted to be tilted upwardly or downwardly in accordance with the 20 governor speed to open or close the circuit between the switch contacts at the ends of the mercury tube.

It is to be understood that the specific type of 25 switch employed and mechanism for opening and closing it is immaterial so long as it will operate satisfactorily and it is to be understood also that these switches are open except when their respective machines are up to operating speed.

30 The dowser mechanism, as employed with each of the machines, is shown best in Figures 10, 11 and 12. This mechanism, in each instance, comprises a housing 25 adapted to be fixed to the machine magazine at a suitable point and from 35 which a guide frame 26 is rigidly suspended. The guide has an opening 27 aligned with the projection lenses and through which the light beam in passing from the machine to the screen is projected. A shutter 28 is adjustable in the guide 40 across this opening to cut off or to permit the light beam to pass to the screen. The shutter in each instance is actuated from and across the opening 27 by means of a connecting link 29 having one end pivotally attached thereto and its 45 other end connected to an arm 30 of a bell crank 31 that is pivotally mounted by a pivot 32 on the back side of the housing 25. Mounted within the housing 25 are paired solenoids with a sliding core bar 34 common to both. From this bar 34, a 50 pin 35 extends rearwardly through a longitudinal slot in the housing wall and into a longitudinal slot 36 in the arm 37 of the bell crank 31. This arrangement of the arm is such that longitudinal shifting of the core bar in opposite directions, 55 incident to energizing one or the other of the solenoids, will, through the pin and slot connection, effect pivotal movement of the bell crank and a resultant opening or closing movement of the shutter that is connected therewith. To make 60 the shutter action quick and positive a tensioned spring 40 is attached at one end of the housing and at its other end to the bell crank arm 30. Movement of the crank in closing or opening the shutter causes the axial line of the spring to pass 65 from one side to the other of the dead center line through the pivot 32 and thereby causes a quick, snapping action of the shutter to one or the other of its limits, prevents rebounds and holds the shutter closed or open. In Figures 1 70 and 4, for better understanding, the dowser shutter of the projector P¹ is designated by character 28a and that for projector P² by character 28b, also in these figures, the dowser solenoids for projector P¹ are designated by S¹ and S² and those 75 for projector P² are designated by S³ and S⁴.

In accordance with this invention, I also provide the reels on which the film strips are wound with automatic switches through which circuits may be established to sound an alarm for warning the operator that the film on the reel is about to become exhausted or as in the modification of Figure 5, later described, to strike the arc of the idle machine. Other switches automatically operate for closing the circuit to the motor of the idle machine to start the latter; the 80 governor of the started machine, after the machine has attained proper speed, operating to close a circuit to the proper solenoids for opening the dowser shutter of the started machine and simultaneously closing the dowser of the operating machine. 90

A reel 12, embodying switches according to the present invention, has been illustrated in Figures 6 and 9. In these figures, 45 designates the reel magazine and 46 the reel hub which carries the side flanges 47—47 between which the film strip, designated at 48, is wound. The magazine is stationary and the reel is supported by the end portion of a tubular shaft 50 to revolve within the magazine, the shaft 50 being revolvably contained 100 in an axial bearing 51 formed by the magazine supporting bracket 52. Fastened to one side of the reel, is a frame 54 on which triggers 55 and 56 are pivotally mounted, as at 57, in a manner which permits each of the triggers to be disposed 105 parallel with the hub axis between successive layers of film that are wound on the reel. As here shown, the trigger 56 is disposed closer to the hub of the wheel than the trigger 55; this being in order that the trigger 56 will operate at 110 some time later than the trigger 55, in practice about 15 seconds later.

At their outer ends, the triggers are pivotally connected, respectively, with push rods 58 and 59 which extend radially of a reel and through a 115 suitable guide 60 adjacent the hub portion and, at their inner ends, they bear against the ends of rocker pawls 61 and 62. These pawls are pivotally mounted in a collar 63 that is fixed on the tubular shaft and they have their inner end 120 portions disposed against the ends of contractor rods 64 and 65 which are slidably contained within the shaft and extend lengthwise and from the end of the shaft, as is shown in Figure 6. Coiled springs 66 and 67 are attached 125 to the push rods 58 and 59 and to the hub of the reel in such manner as to pull inwardly on the rods; the arrangement being such that, with the triggers disposed between layers of the film wound on the reel, the rods will be held at their 130 outward limit against tension of the springs, but when the film unwinds and releases the triggers, the latter will swing outwardly and the rods will be pulled inwardly to thereby rock their respective pawls to shift the contractor rods lengthwise 135 with the shaft. The inner ends of the contractor rods, as shown in Figure 7, are reduced and are slidable through a plug 69 that is fitted in the end of the shaft 50, and springs 70 and 71 are disposed about the reduced portions of the rods to 140 bear against the plug and against shoulders formed on the rods to thereby retain the rods in contact with their respective pawls.

Fixed on the axle portion of the bracket 52, see Figures 6 and 7, is a yoke 73 which, at its end, 145 carries a plate 74 of nonconductive material with an opening 75 therein within which the end of shaft 50 is revolvable. This plate serves as a mounting for two pairs of binding posts 76—76' and 77—77'; these posts being in separate cir- 150

cuits presently described. Yieldable plates 78 and 79 are carried by the posts 76 and 77 and these are adapted to be pressed into circuit closing contact with plates 80 and 81 carried, respectively, by the posts 76' and 77' by means of the contractor rods 64 and 65 on release of the triggers. The plates 78 and 79 in this arrangement serve as circuit control switches and, in the diagrammatic view of Figures 1, 2, 3 and 5, these switches, for the reel of projector P¹, are designated at 78a and 79a and, for the projector P², they are designated at 78b and 79b; the switches 78a and 78b being those which are under control of the outer triggers and close their circuits on unwinding of the film from a reel prior to the closing of the switches 79a and 79b.

Associated with the reel switches, as in Figures 1 and 2 is an electrically operated buzzer 85. This is connected by wires 86 and 87 with a transformer 88 and the transformer is connected, as presently described, with what is termed the buzzer circuit. This circuit, as shown in Figures 1 and 2, includes switches 89 and 90 which are associated, respectively, with the switch levers 7 and 9 of the arc circuits and their relationship is such that manual adjustment of either lever 7 or 9 from open to circuit closing position permits an automatic opening of its corresponding switch 89 or 90, and likewise adjustment of either lever to open its arc circuit effects the closing of the corresponding switch 89 or 90.

Electric circuit for the control system and motors is supplied by wires A and B from any suitable circuit, which might be the usual house lighting circuit. The circuit of motor M¹ flows from wire A through wire 100 to one side of the motor and returns through a wire 101 from the other side of the motor to a contact 102 that is adapted to be connected through a solenoid actuated switch lever 103 with the circuit wire B. Current for the motor M² flows from the wire A through a wire 105 to one side of the motor and returns through a wire 106 to a contact 107 adapted also to be connected through the switch lever 103 to wire B. The switch lever 103 as shown in Figure 3, has permanent electrical connection with the wire B and is pivotally mounted so as to permit its being shifted by mechanism operating under control of switches 79a and 79b to direct the current through one or the other of the motors.

This control mechanism as shown in Figures 1 and 3, comprises a pair of solenoids 108 and 109. These have a sliding core bar 110 common to both and the core, incident to its movement in opposite directions, operates through a cross bar 111 having pin and slot connections, as at 111¹, to swing the lever 103 between the contacts 102 and 107 and also to swing a similar, pivotally mounted switch arm 112 between fixed contacts 113 and 114; lever 112 also being electrically connected with wire B. The solenoids, 108 and 109, are operable under control of the reel switches 79a and 79b, and their function is to throw the switch arms 103 and 112 so as to cut in the circuit of an idle motor incident to the closing of the reel switch of the operating projector. To accomplish this result, see Figure 3, the switch 79a is connected at one side by wire 118 to the wire A. The other side of the switch 79a is connected by a wire 119 with the outer end pole of the solenoid 109. Likewise, one side of switch 79b is connected by a wire 120 with the wire A and its other side is connected by a wire 121 with the outer end pole of the solenoid 108. The

inner pole of this latter solenoid is connected by a wire 122 with the contact 114. Likewise, the inner pole of the solenoid 109 is connected by a wire 124 with the contact 113.

The buzzer control circuit, see Figure 2, consists of a connection through wires 118 and 130 from wire A to one side of switch 78a and a similar connection through wires 120 and 131 to one side of switch 78b. The other pole of switch 78a is connected by wire 132 with the outside pole of switch 90, which in turn has its inner pole connected by a wire 133 with the inner pole of the switch 89 and this, in turn, has its outer pole connected by a wire 134 with the other pole of switch 78b. The transformer 88, which is under control of the buzzer circuit, is connected by wires 135 and 136, respectively, with wire 133 and wire B.

Now, assuming the projector P² and motor M² to be in operation, with switches 78b and 79b and 90 open; and assuming projector P¹ and motor M¹ to be idle but ready to start with switches 78a, 79a open and switch 89 held closed by switch lever 7 as in Figure 1; the motor circuit flows to motor M² from wire A, see Figure 3, through wire 105 and returns through wire 106, contact 107, switch lever 103, to wire B. As the film strip unwinds from reel 12 of projector P² it finally permits closing of switch 78b. This closes a circuit to the transformer for energizing the buzzer; the circuit passing from wire A, see Figure 2, through wires 120, 131, switch 78b, wire 134, switch 89, wires 133 and 135 to the transformer 88 and through wire 136 to wire B. This causes the buzzer to be energized and receiving the buzzer signal, the operator immediately strikes the arc of projector P² by throwing the switch lever 7 over against contact 8, and this permits opening of the switch 89 and thus opens the buzzer circuit.

Following the closing of the buzzer signal switch 78b, there is a continued unwinding of film from reel 12 and preferably, after about fifteen seconds, the switch 79b is closed. This causes current to be directed through solenoid 108, see Figure 3, to momentarily energize it and shift core bar 110 to thereby throw the switch arms 103 and 112 to their opposite positions against contacts 102 and 113 as in dotted lines in Figures 1 and 3, to close the circuit through motor M¹, to start operation on projector P¹. On closing of switch 79b, current flows from wire A, through wires 120, switch 79b, wire 121, solenoid 108, wires 122, contact 114, arm 112, to wire B. This completes the circuit, energizes the solenoid 108 and causes bar 110 to shift to the left and, in so doing, to throw the levers 103 and 112 against the contacts 102 and 113; this being done by mechanism shown in Figures 1 and 3. Current then flows to motor M¹ from wire A through wire 100, and returns through wire 101, contact 102 and lever 103 to wire B.

In order that this operation of the solenoid may not cut off motor M², since it is desired that it continue to operate for a short time to run out the tail end of film strip, I have provided a shunt circuit embodying a three point switch 139 having a switch lever 140 connected by wire 141 with wire B, and having contacts 142—142¹ connected respectively by wires 143 and 144 with the contacts 102 and 107. When lever 103 breaks contact with contact element 107, then current for motor M² may continue to flow from contact 107, through wire 144, switch lever 140 and wire 141 to wire B. After the tail end of the film

- of projector P^2 has been run out, then the motor M^2 is manually cut out by throwing switch lever 140 so that it breaks connection with contact 142¹. It is then engaged with contact 142 to be ready for the changeover from motor M^1 back to motor M^2 . When the machine P^2 is stopped, the arc switch lever 9 is opened to cut off the circuit to the electrodes E^a and E^b while the machine is idle.
- 10 The sounding of a buzzer signal and a following changeover from motor M^1 back to motor M^2 would be accomplished in a similar way to that above described, incident to closing of switches 78 a and 79 a in the reel 12 of projector P^1 .
- 15 In the instance of the buzzer signal being closed by release of switch 78 a , the signal would be cut off by the operator throwing the lever 9 to close the circuit to electrodes of projector P^2 . The motor circuit for M^2 would subsequently be cut in by the closing of switch 79 a which causes a momentary energizing of solenoid 109 to throw switch levers 103 and 112 back into the contacts 107 and 114. Cutting out of the circuit to motor M^1 after running out of the film, is accomplished by reversing switch lever 140 to open the connection with contact 142.
- 20 The dowser shutters 28 a and 28 b are operated by circuits under control of the speed governors 18 g on the projectors P^1 and P^2 and the closing 25 of the shutter of one machine and the simultaneous opening of the dowser of the other machine is occasioned by the started machine attaining its proper operating speed which closes its switch 20 a or 20 b .
- 25 The dowser control circuits are shown best in Figure 4, and are as follows: One pole of the solenoid S^1 is connected to wire A by wires 150 and 118. Likewise, one pole of the solenoid S^4 is connected to wire A by wires 151 and 120. A wire 30 152 connects together the remaining poles of solenoids S^1 and S^4 . A wire 153 connects corresponding poles of solenoids S^2 and S^3 , and their other poles are connected to wire A by wires 154—118 and 155—120 respectively. The core 35 bar 34 a of solenoids S^1 and S^2 which actuates the shutter 28 a also actuates a mercury switch 160 to open and close a circuit that is provided between the switch 20 a and the outer pole of solenoid S^1 through wires 161 and 162; this switch 40 160 being closed when the shutter is closed. Likewise the core bar 34 b of solenoids S^3 and S^4 which actuates the shutter 28 b operates a mercury switch 163 to open and close a circuit connection provided between switch 20 b and the outer pole 45 50 55 60 65 70 75 80 85 90 95 100 105 110 115 120 125 130 135 140 145 150 155 160 165 170 175 180 185 190 195 196 197 198 199 200 201 202 203 204 205 206 207 208 209 210 211 212 213 214 215 216 217 connection. The purpose of extending these connections to the lower contacts is to avoid flickering of the shutters after a changeover is made. It is quite apparent if wires 166 and 167 extended 5 to contacts 102 and 103, respectively, a changeover from one machine to the other would result in a reciprocating action of the core bars 34a. The method of connecting, as shown in Figure 4, overcomes this possibility.

10 In some instances, it may be desirable to employ an automatic means for striking the arc of the machine to be started. In Figure 5, I have illustrated diagrammatically a circuit and devices for effecting this automatic closing of the arc 15 switches 7 and 9. In this arrangement switch lever 7 is moved from open to closed position by shifting of the core 196 or a solenoid 197, and the switch lever 9 is likewise actuated by a core 198 of a solenoid 199. The switch 78a 20 is connected at one side to the wire A through a wire 200, and it is connected at the other side by a wire 201 to one pole of the solenoid 199, the other pole of the solenoid being connected by a wire 202 to the wire B. Likewise, one side 25 of the switch 78b is connected to the wire A by a wire 204 and its other side connects by wire 205 with one side of solenoid 197. The other side of the solenoid connects to wire B through a wire 208.

30 In this above arrangement when switch 78b closes incident to unwinding of film from the reel 12 in the projector P², a circuit will be closed through the solenoid 197 to close the switch 7 to thereby strike the arc of the projector P¹. Likewise, when switch 78a closes, a circuit is closed 35 through the solenoid 199 to close the switch 9 to strike the arc of the projector P². Opening of these switches is manual and would be done at the same time that the motor for the operating machine is shut down.

By using the above-described circuits and devices it is readily apparent that an automatic operation is effected whereby the operator of machines is first warned of the approach of the 45 end of the film strips so that he may strike the arc of the idle machine in plenty of time for it to be properly heated when the machine is set in operation. Following this automatic operation of the various switch devices placed to start the 50 idle machine, and after it has attained proper speed to simultaneously open its shutter mechanism and to close that of the operating machine.

Having thus described my invention, what I claim as new therein and desire to secure by 55 Letters Patent, is:

1. In combination with two motion picture machines arranged for alternate operation and each embodying a film feed reel and an operating motor, a main circuit, a normal operating circuit 60 for each motor, an electrically actuated changeover mechanism connected in the main circuit and operable to deliver current to one or the other of said motors, said changeover mechanism comprising a pair of spaced contacts connected, respectively, with the two motors, a switch arm movable from one contact to the other to cause current to flow through one or the other of the motors, a pair of solenoids operatively connected for moving the switch arm, circuits for the solenoids associated, respectively, with the film feed 65 reels of the two machines and each including a switch operable incident to unwinding of a predetermined amount of film from the operating machine to close its circuit to actuate the switch arm to close a circuit through the motor of the

idle machine and to open the normal operating circuit to the motor of the operating machine, a second switch actuated by the solenoids simultaneous with the movement of the switch arm, thereby to open the circuit of the energized solenoid. 80

2. A device as in claim 1 wherein shunt connections are provided from the said contacts across the switch arm of the changeover mechanism and a manually operable switch is interposed in said shunt connections through which circuit connection may be made or opened with either of said motors independent of the changeover mechanism. 85

3. In combination with two motion picture machines arranged for alternate operation and each including a film feed reel and an operating motor, an electric circuit for the motors having direct connection with one side of each motor, a changeover mechanism comprising a pair of spaced contacts having circuit connections, respectively, with the other sides of the motors, a switch arm connected with said other side of the circuit and movable from one contact to the other, a pair of solenoids, a core bar for the solenoids connected 100 to move the switch arm, circuits for the solenoids including switches associated, respectively, with film feed reels and each operable incident to the unwinding of a predetermined amount of film to close the circuit of its solenoid to move the switch arm to thereby close a circuit through the motor of the idle machine and to open the circuit of the motor of the operating machine, and a second switch arm common to both the solenoid circuits and movable by the core bar 110 to open the circuit of the energized solenoid. 105

4. The combination with two motion picture machines arranged for alternate operation and each including a film feed reel, an arc circuit and a switch for controlling its arc circuit, of a signal circuit associated with each of the machines and each rendered operative by the opening of the arc circuit switch of the opposite machine and each including a normally open switch associated with the film feed reel operable incident to 115 the unwinding of a predetermined amount of film, to automatically close the circuit to the signal. 120

5. The combination with two motion picture machines arranged for alternate operation and each embodying a film feed reel, an arc circuit and a switch element movable to open or close the arc circuit, of a signal circuit associated with each machine and each including a normally open switch that is automatically operable, incident to the unwinding of a predetermined amount of film from the film feed reel to close the signal circuit and a second switch which is designed to be held closed by the open switch element in the arc circuit of the idle machine and adapted 130 to open incident to adjustment of this element for closing its arc circuit. 135

6. In combination with two motion picture machines, each comprising a film feed reel, an operating motor, a governor device and a shutter movable from and across its line of projection, an electric circuit for the motors, a changeover mechanism for directing current to one or the other of said motors, control means for the changeover mechanism including switches associated with the feed reels and operable incident to unwinding of a predetermined amount of film to start the motor of the idle machine, electric actuating devices for each shutter to move it between open and closed positions, electric cir- 140

cuits for said devices, normally open switches in said circuits operable by the said governor device of the started machine to close the circuit to simultaneously cause opening of the shutter 5 of the started machine and closing of the shutter of the other, and other switches in the circuits movable by the shutter actuating devices to open the circuits after reversal of the shutters.

7. In a system of the character described, employing 10 a plurality of control circuits, a reel supporting bracket having a hub portion, switch mounting means fixed to the bracket, a tubular shaft rotatably mounted in the hub and extended at one end to the switch mounting means, a 15 film reel mounted on the other end of the shaft, a trigger frame fixed to the reel, spring actuated triggers fixed to the frame and adapted to be

held in set position by the film strip wound on the reel and to be released by the removal of a predetermined amount of film therefrom, switches mounted by said switch mounting means and connected in said control circuits, push rods for closing the switches extended thereto through the said tubular shaft and having operative connection with the said triggers. 80

8. A device as in claim 7 wherein bell cranks are mounted on the tubular shaft and operatively engage the push rods and have operative connection with the triggers, and where shoulders are formed on the push rods and springs bear against said shoulders for yieldably retaining the push rods in retracted position. 85
